UNITED STATES PATENT OFFICE.

GEORGE W. SHOEMAKER, OF DALTON, PENNSYLVANIA.

WASHBOARD.

1,311,624.

Specification of Letters Patent. Patented July 29, 1919.

Application filed September 13, 1918. Serial No. 253,923.

To all whom it may concern:

Be it known that I, GEORGE W. SHOEMAKER, a citizen of the United States, residing at Dalton, in the county of Lackawanna 5 and State of Pennsylvania, have invented a new and useful Washboard, of which the following is a specification.

This invention relates to wash boards, one of its objects being to provide a device of 10 this character having a soap receptacle so positioned that the fabric, while being rubbed, can be moved over the soap.

A further object is to provide a rubbing board which can be adjusted relative to the 15 soap holder, thus to cause the held soap to project the desired distance beyond the rubbing surface.

With the above and other objects in view, the invention consists in certain novel design 20 tails of construction and the combination of parts which will be hereinafter more fully described and pointed out in the claims, it being understood that various changes may be made in the construction 25 and arrangement of the parts without departing from the spirit or sacrificing any of the advantages of the invention as set forth in the attended claims.

In the accompanying drawings the preferred form of the invention has been shown.

In the drawings Figure 1 is a front elevation of the wash board.

Fig. 2 is a longitudinal section there- 35 through, said section being taken on the line 2—2 of Fig. 1.

Fig. 3 is a section on the line 3—3 of Fig. 2.

Referring to the figures by characters of 40 reference 1 designates side strips which are connected at one end by a top strip 2 and at an intermediate point by a cross strip 3. A longitudinal recess 4 is formed in the inner side of each of the strips 1 and extends from 45 the cross strip 3 to a point adjacent the top strip 2, this recess providing a front wall 5 extending throughout the length thereof while the rear of the recess is open, except at the bottom thereof where the recess is 50 provided with an extension projecting into the cross strip 3.

A rubbing board 7 is mounted on the cross strip 3 and has its side edges projecting into the recesses 4, this rubbing board being pro- 55 vided with a front corrugated surface 8 of

metal or the like. One or more reinforcing strips 9 may be secured to the back face of the rubbing board. Secured to rear edges of the side strips 1 is a back board 10 which may be provided with a reinforcing strip 11 60 and extending through this strip and the back board are adjusting screws 12, the front ends of which bear against the upper end portions of the rubbing board. By means of these screws the rubbing board can be 65 brought forwardly into engagement with the front walls 5 of the recesses 4. A strip 13 is secured between the upper end portions of the side strips 1 and is inclined downwardly and backwardly by the top strip 2, 70 thus to form a pocket 14 above the rubbing board.

An opening 15 is formed in the rubbing board near the upper portion of the center thereof and directly above the reinforcing 75 strip 9; and secured to the back board 10 directly back of the opening 15 is a corrugated plate 16.

In using this device a cake of soap is placed in the opening 15 so as to be supported by the strip 9 and abut against the plate 16. The rubbing board is then adjusted forwardly against the wall 5 of the recesses 4 by rotating the screws 12. This will bring the surface of the rubbing board substantially flush with the front surface of the cake of soap. Thus the soap will be engaged by the fabric rubbed over the board and, as the soap wears away, the screws 12 can be gradually unscrewed, thus to allow 80 the board 8 to move back from the walls 5 and expose another portion of the held cake of soap. During the adjustment of the board it will of course swing about the lower end thereof which is anchored in the 85 extension 6 of each recess 4.

What is claimed is:

1. A wash board including side strips having recesses therein, a stationary soap holder supported between the side strips, a 100 rubbing board supported between and extending into the recesses within the side strips and having an opening into which the held soap will project, and adjustable means for holding the rubbing board against backward movement within the recesses.

2. A wash board including recessed side strips, connections therebetween, each of the recesses having an extension at its lower end, a back board connecting the side strips, 110

a rubbing board projecting at its sides in of the rubbing board for restricting the movement of the rubbing board within the recesses and supported at its lower end within the extensions, said rubbing board having an opening therein, a soap supporting strip upon the back of the rubbing board and constituting a reinforcement for said rubbing board, a backing plate upon the back board and in rear of the opening for engagement by a supported cake of soap, and adjusting screws extending through the back board and engaging the upper portion

In testimony that I claim the foregoing 15 as my own, I have hereto affixed my signature in the presence of two witnesses.

GEORGE W. SHOEMAKER.
